UNITED STATES PATENT OFFICE.

ADOLF HALSTRICK, OF COLOGNE, GERMANY.

TABULATING DEVICE FOR TYPE-WRITERS.

SPECIFICATION forming part of Letters Patent No. 735,367, dated August 4, 1903.

Application filed January 2, 1902. Serial No. 88,081. (No model.)

To all whom it may concern:

Be it known that I, ADOLF HALSTRICK, a subject of the King of Prussia, German Emperor, residing at Cologne, in the Kingdom of Prussia, Empire of Germany, have invented a new and useful Tabulating Device for Type-Writers, of which the following is a specification.

My invention relates to improvements in tabulating devices for type-writers; and the objects of my improvement are, first, to provide the paper-roll carriage with a feeding-rack adapted to swing around a parallel horizontal axis placed in the longitudinal direction of the carriage; second, to provide means for holding said swinging feeding-rack in engagement with the feeding means; third, to provide a horizontal scaled axle parallel to said swinging feeding-rack and carrying two arms and between them an internal rack whereby a rectangular frame is formed; fourth, to arrange the one of said two arms for lifting the feeding-rack out of engagement with the feeding means and thereby releasing the carriage; fifth, to provide means for transmitting the movements from the tabulator-key to the said one arm; sixth, to provide a plurality of narrow adjustable stops on the scaled axle and the internal rack and engaging the latter, and, seventh, to provide the carriage with a swinging stop so arranged as to strike against either adjustable stop for stopping the carriage while it is capable of being raised out of the way by either adjustable stop. I attain these objects by the mechanism illustrated in the accompanying drawings, in which—

Figure 1 is a vertical cross-section through the rear part of the frame of a type-writer and through the paper-roll carriage on the line A B in Fig. 3, the parts of the tabulating device being shown in their usual positions when at rest. Fig. 2 is a similar cross-section on the same line to show the parts of the tabulating device in their respective positions on the tabulator-key being depressed. Fig. 3 is a plan of the same. Fig. 4 is a vertical cross-section of the same on the line C D in Fig. 3. Fig. 5 is an elevation of the swinging stop, on an enlarged scale. Fig. 5^a is an end view of the same. Fig. 6 is a plan of the

same and a part of the carriage. Fig. 7 is a vertical longitudinal section, on an enlarged scale, through an adjustable stop on the line E F in Fig. 8; and Fig. 8 is a plan of the same with parts of the scaled axle and the internal rack.

Similar letters of reference refer to similar parts throughout the several views.

In the drawings I have shown the new tabulating device as applied to a box-shaped frame used in various well-known type-writers; but it will be understood that the new device can also be applied to other kinds of type-writer frames. All the other parts of the type-writer are omitted from the drawings, as they form no part of my invention. The paper-roll carriage *h* is assumed to be guided horizontally in any well-known manner, but not shown in the drawings, while the paper-roll (not shown) may be arranged for being raised and lowered, as usual.

On the carriage *h* a U-shaped frame *k'* (see Fig. 3) is mounted to turn on pins *i*. To this frame a feeding-rack *k* is affixed, which thus swings around a horizontal axis in the longitudinal direction of the carriage *h*. The swinging feeding-rack *k* engages with either the stationary pawl *z'* or the movable pawl *z*, mounted on the rocking lever *o*. Preferably a leaf-spring *k²* is inserted between the carriage *h* and the longitudinal part of the frame *k'*, so as to hold the swinging feeding-rack *k* in engagement with either pawl *z* or *z'*. The rocking lever *o* is assumed to be mounted to turn on pins *o⁰*, provided on suitable arms *a'* of the machine-frame. This lever *o* is further assumed to be actuated from either key-lever in any known manner—for example, by means of a rod *o'* (see Fig. 4) and a lever *o²*, of which latter only a part is shown. On depressing any of the keys by the respective transmitting means the rocking lever *o* will be moved in the direction of the arrow 2 in Fig. 1, and on the key being again released the lever *o* will be moved backward. Thereby in the usual manner the carriage *h*, with the swinging feeding-rack *k* and the paper-roll, will be fed forward under the action of the respective spring.

The rear part *a* of the machine-frame is provided with two end supports *b b*, on the

upper ends of which the scaled axle c is mounted to turn by means of a pointed pin b' and a pointed adjusting-screw b^2 . (See Fig. 3.) The scaled axle c carries two arms d and e , between which the internal rack f is secured, the whole forming a rectangular frame swinging around the axis of the axle c . The one arm e extends beyond the internal rack f and is shaped somewhat like a hook, (see Fig. 1,) so as to nearly touch the frame k' , while leaving free room for the rack k traveling longitudinally. The front end of the lever e is provided with a projection n , placed parallel to the longitudinal-part of the frame k' and covered with leather, so as to serve as a brake. The tabular-key lever m , of which only the rear part is shown, swings around the pin m^0 and is pressed upward by a spring p . It is pivotally connected with the hook-shaped lever e by means of the rod m' , the lever m^2 , the shaft m^3 , the lever e^2 , and the rod e' .

On the scaled axle c and the internal rack f several (in the drawings two) narrow adjustable stops g are mounted to slide. For shifting either adjustable stop g its pawl t is withdrawn from the rack f by means of the head u , and on the latter being again released the pawl t engages the respective tooth-space.

On the carriage h the swinging stop l is mounted to turn on the pin v , (see Figs. 5 and 6,) and its movement is limited by a screw w , secured in the carriage h and engaging the slot w of the stop l . The free end l' of the swinging stop l is bent rearward and so much that it can strike against either adjustable stop g when the latter is raised.

The tabulating device is operated as follows: The two adjustable stops g are adjusted according to the scale on the axle c and in correspondence with the places on the paper where the first types of the columns are to be printed. On depressing the tabular key, and thereby also its lever m , the projection n of the lever e will by the parts m' , m^2 , m^3 , e^2 , e' , and e be moved in the direction of the arrow 1, so as to lift the swinging feeding-rack k out of engagement with the feeding-pawls $z z'$. Thereupon the carriage h will be released, so that under the action of the respective spring it will move forward until the bent end l' of the swinging stop l strikes against the first adjustable stop g , when the carriage will be stopped. (See Fig. 2.) For regulating the speed of the moving carriage the tabular key can be more or less strongly depressed, so as to press the projection n , covered with leather, against the frame k' , whereby a certain amount of friction is produced. On again releasing the tabular key the various parts m , m' , m^2 , m^3 , e' , e , and k with k' are returned to their initial positions, partly by their own weights and partly by the spiral spring p . Then the movable pawl z will engage the feeding-rack k , and on depressing the respective keys the carriage h will be fed forward, while the corresponding

types are printed on the paper. When the last type of the column has been printed, the tabular key is again depressed, so as to cause the carriage h to move forward until it is again stopped by the bent end l' of the stop l striking against the raised second adjustable stop g . Should the bent end l' happen to be still above the first adjustable stop g , (see Fig. 4,) this circumstance would not prevent the tabular key from being depressed. The raised first adjustable stop g would merely lift the swinging stop l in the direction of the arrow 3 in Fig. 5, and on the carriage h moving forward the bent end l' will soon leave the raised first adjustable stop g and drop, so that it can strike against the second adjustable stop g and stop the carriage. If it is desired to write nothing in the first column, but something in the second column, all that is required is merely to depress the tabular key until the carriage stops for the first time, then to release and again to depress the tabular key. The adjustable stops g being narrow, it is possible to print types in narrow columns. The reason is that the bent end l' of the swinging stop l is very small, (see Fig. 6,) and therefore the two stops g can be placed so near each other as to leave just sufficient room for the bent end l' engaging between them upon depressing the tabular key, so that the bent end l' will strike against the second stop g , and thus stop the carriage. This means that in this case the tabular column is the narrowest and its width is equal to the distance from the right-hand face of the second stop g to the right-hand face of the first stop g . The stops g present the advantage that they will stop the carriage h safely, since the teeth of the internal rack f , in which the pawls t engage, are very near the places against which the bent end l' of the swinging stop l strikes.

Of course more than two adjustable stops g may be employed. Preferably they are not made in one piece, as shown, but in two pieces, or they are so shaped that they can be put over the scaled axle c and the internal rack f and again taken off without taking the swinging frame $c d e f$ to pieces.

What I claim as my invention, and desire to secure by Letters Patent, is—

1. In a type-writer, the combination with a carriage, of two levers on left and right ends of said carriage, a feeding-rack secured between said two levers, a feeding mechanism therefor, means for pressing downward said feeding-rack and holding it in engagement with said feed mechanism, a turnable rear shaft in the machine-frame parallel to said carriage, a rectangular frame secured on said rear shaft, a plurality of adjustable stops on said rectangular frame, means for transmitting the movement from the tabular key to said rear shaft, an arm fastened on said rear shaft for raising said feeding-rack out of engagement with said feed mechanism on the tabular key being depressed, a swinging stop on the rear of said carriage for striking against

either of said adjustable stops, and means for limiting the downward movement of said swinging stop, substantially as set forth.

2. In a type-writer, the combination with a carriage, of two levers on left and right ends of said carriage, a feeding-rack secured between said two levers, a feed mechanism therefor, means for pressing downward said feeding-rack and holding it in engagement with said feed mechanism, a turnable rear shaft in the machine-frame parallel to said carriage, a rectangular frame secured on said rear shaft, a plurality of adjustable stops on said rectangular frame, means for transmitting the movement from the tabular key to said rear

shaft, an arm fastened on said rear shaft for raising said feeding-rack out of engagement with said feed mechanism on the tabular key being depressed, said arm serving at the same time as a brake for said carriage, a swinging stop on the rear of said carriage for striking against either of said adjustable stops, and a pin for limiting the downward movement of said swinging stop, substantially as set forth.

In witness whereof I have hereunto set my hand in presence of two witnesses.

ADOLF HALSTRICK.
